WITNESS:

INVENTOR
vans
ATTORNEY

UNITED STATES PATENT OFFICE

JOHN W. CARTER, OF NEILLSVILLE, WISCONSIN

AUTOMATIC WEATHER STRIP FOR DOORS

Application filed August 26, 1929. Serial No. 388,525.

The invention relates to the broad class of builders hardware, particularly to weather excluding devices, and has for its general object the provision of a novel weather strip device adapted to be mounted upon the bottom portion of a door and acting automatically to contact with the threshold when the door is closed for the purpose of providing a weather proof joint which will exclude cold wind or rain, the device being also of such construction that when the door is opened the weather strip will be automatically raised to inoperative or ineffective position out of the way.

An important object of the invention is to provide an automatic weather strip device of this character which is spring operated in one direction and moved in the other direction by engagement of an operating element against the door jamb.

Another object is to provide a mechanism of this character which is entirely housed upon one side of the door and which will therefore be concealed from view so as not to detract in any way from the ornamental appearance of the door itself.

An additional object is to provide a device of this character which will be simple and inexpensive to make, easy to install or assemble, positive in action, efficient and durable in service, and a general improvement in the art.

With the above and other objects and advantages in view, the invention preferably consists in the details of construction and the arrangement and combination of parts to be hereinafter more fully described and claimed, and illustrated in the accompanying drawing, in which:—

Figure 1 is an elevation of a door in open position, the view being taken transversely of the threshold and showing the weather strip device in withdrawn or ineffective position.

Figure 2 is a similar view with the cover removed.

Figure 3 is an elevation of the door and its jamb with the cover removed and showing the weather strip device in lowered or operative position.

Figure 4 is a vertical cross section taken on the line 4—4 of Figure 3.

Figure 5 is a similar view showing the weather strip device withdrawn or inoperative position.

Figure 6 is a detail perspective view of one of the operating brackets.

Figure 7 is a detail elevation looking at one end of the weather strip with the operating element thereon.

Figure 8 is a detail perspective view of the operating rod.

Referring more particularly to the drawing, the letter A designates a door, B represents the jamb to which the door is hinged at C, D indicates the opposite jamb and E the threshold. In carrying out the invention I cut away the threshold E as indicated at 10 to provide an abutment shoulder 11 and secure upon the threshold a metal strip 12 so as to have a clearly defined edge against which abuts the weather strips to be described.

The weather strip itself is indicated by the numeral 13 and preferably comprises an elongated metallic plate bearing on its face toward the door a felt or other yieldable liner 14. The recess or cut away portion of the threshold and the weather strip are so related or located with respect to each other that the felt liner 14 is adapted to engage upon the top of the metal strip 12 while the metal strip or plate 13 engages against the edge thereof. Secured upon the side of the door are suitable guides 15 thru which is longitudinally slidably mounted an operating rod 16 formed with a plurality of holes 17 and 18. This rod is positioned so as to engage at one end against the door jamb B when the door A is moved into closed position as shown in Figure 90

3. Pivotally mounted upon the door, as by means of screws 19 or the like are bracket members 20 shown in detail in Figure 6, each of these bracket members being here represented as formed from a single length of wire bent to define arms 21 and 22 connected by a convolution or coil 23, the arm 22 terminating in a reflectedly or reversely bent portion defining a loop 24. The convolutions 23 of these bracket members are engaged upon the screws 19 so as to be pivoted, and the arm 21 passed thru the holes 15 in the rod 16. Suitably secured upon the strip or plate 13 are brackets 25 which project above the upper edge thereof and which have laterally extended upper ends 26. The loop 24 of the brackets 20 are engaged upon the upper ends of the bracket 25 and are prevented from accidental disengagement therefrom by means of the lateral extensions 26.

19 15 20 Suitably mounted, as at 27, upon the door is a spring device 28 which may be of right angular shape including an arm 29 extending thru the hole 18 in the rod 16 and also including an arm 30 having a curved end engaging against a stop 31 on the door.

30 35 In order to protect the mechanism and to conceal it from view I preferably provide a cover or housing 32 which may be conveniently formed of sheet metal finished in any desired manner and secured upon the door in such position as to cover the above described parts 13 to 31. This cover is represented as having an attaching flange portion 33 secured to the door as by means of fastening elements 34, such as screws or the like passing thru this attaching flange and into holes 35 in the door.

40 45 Assuming that the device has been constructed and installed as above described and as shown in the drawing, it will be seen that under ordinary circumstances the spring 28 will operate to urge the rod 16 toward the jamb B. However, when the rod is urged in this direction it is apparent that the members 20 which are in effect bell cranks will be shifted in one direction so as to exert an upward pull upon the brackets 25, thereby holding the weather strip 13 in its elevated 50 55 position out of engagement with the threshold or door sill. There is consequently nothing at this time to interfere with the partial or entire closing movement of the door. However, when the door is swung into its closed position the end of the rod 16 nearest the jamb B will engage against this jamb directly or against an adjustable abutment 36 thereon, the result being that the rod 16 will be shifted longitudinally in the opposite direction, placing the spring 28 under tension and at the same time moving the angle bracket members or bell cranks 20 in such direction that the arms 22 thereof co-operating with the brackets 25 force the latter and consequently the weather strip 13,

with its felt liner 14, downwardly into engagement with the threshold or door sill at the cut away portion thereof, the metal strip or plate 13 of the weather strip engaging against the shoulder 11 and the felt liner 14 70 engaging upon the top of the metal plate 12. At such a time it is quite apparent that the weather strip will constitute an effectual seal for excluding drafts, dust, water or the like. The principal consideration is, of course, the exclusion of cold air in winter time and it is readily apparent that the device will function in the manner described and for the purpose set forth. When the door is subsequently opened the tension of the spring 28 will 75 operate to return the rod 16 and the other parts to the initial or normal position with the weather strip elevated out of engagement with the door sill or threshold. It is really believed that the construction, operation and 80 advantages will be apparent from the foregoing without further explanation.

While I have shown and described the preferred embodiment of the invention, it should be understood that I reserve the right to make all such changes in the details of construction and the arrangement and combination of parts as will not depart from the spirit of the invention or the scope of the subjoined claim.

Having thus described the invention, I claim:—

The combination with a swinging door and its frame, including a door sill and a wear plate upon the upper side of the sill, 100 and which sill is recessed at its upper side in rear of said plate, of a rod mounted transversely upon the door at the inner side of said door, a weather strip comprising a plate of metal and a facing of packing material 105 upon one side of said plate, arms secured to the outer side of said plate and extending over the upper edge thereof and thence upwardly and provided at their upper ends with inwardly directed right angular extensions to engage the surface of the door against which the facing strip is disposed, the facing strip being so positioned with respect to the lower edge of the plate that the lower edge of the strip will seat upon the 110 upper side of the wear plate and the lower edge of the said weather strip plate will project below the lower edge of the facing strip to seat in the recess in the sill of the door frame, resilient members mounted for rocking movement between their ends upon the outer side of the door, the members each having an upstanding arm and the rod having openings into which the ends of the arms project, each of said members further comprising an arm extending at an angle to the first mentioned arm and provided with a loop to slidably engage the upstanding portion of the respective arm upon the plate and beneath the terminal extension of said arm 120 125 130

whereby to support the plate in elevated position, and a coiled spring upon the door having one end engaging the said rod and its other end fixed with respect to the door and holding the rod shifted in a direction to maintain the weather strip unit normally in an elevated position, and an abutment upon the jamb of the door frame to which the door is hinged, positioned to be engaged by one end of the said rod when the door is swung to closed position whereby to shift the rod against the tension of said spring and effect lowering of the weather strip unit into engagement with the sill.

15 In testimony whereof I affix my signature.
JOHN W. CARTER.
